[57] CLAIM

The ornamental design for a bulk food dispenser, substantially as shown and described.

DESCRIPTION

FIG. 1 is a perspective view of a bulk food dispenser showing my new design;

FIG. 2 is a top plan view thereof;

FIG. 3 is a front elevational view thereof;

FIG. 4 is a right side elevational view thereof, the left side being the mirror image of that shown; and

FIG. 5 is a rear elevational view thereof.

The bottom surface of the bulk food dispenser is plane and unornamental.

FIG. 1

FIG. 2

FIG. 3

FIG. 4

FIG. 5
